UNITED STATES PATENT OFFICE.

DEXTER W. PARKER AND LEWIS F. GRISWOLD, OF MERIDEN, CONNECTICUT,
ASSIGNORS TO THE CHARLES PARKER COMPANY, OF SAME PLACE.

DESIGN FOR A LAMP-HARP.

SPECIFICATION forming part of Design No. 15,640, dated December 23, 1884.

Application filed June 24, 1884. Term of patent 14 years.

To all whom it may concern:

Be it known that we, DEXTER W. PARKER and LEWIS F. GRISWOLD, both citizens of the United States, residing at Meriden, in the county of New Haven and State of Connecticut, have invented and produced a new and original Design for Lamp Harps or Supports, of which the following is a specification, reference being had to the accompanying drawing, forming part thereof.

The said drawing represents a harp formed according to said design, and shown in front elevation.

The leading feature of said design consists of two triangular ornamental pieces on opposite sides of the harp, as shown.

A designates the harp, having approximately the shape of a **V** or narrow **U**. At the bottom is an ornamental piece, N, consisting partly of triangles. The sides of said harp present two right-angled triangles, M—one on each side—these triangles being counterparts of one another, and being provided with ornamental figures *m*, as shown. These represent a bird, flowers, leaves, and decorative lines.

Having thus described our design, what we claim as new, and desire to secure by Letters Patent, is—

1. A design for a lamp-harp, consisting of a harp approximately **V**-shaped, as shown, and provided at the sides with ornamental triangles M, representing a bird, flowers, leaves, and decorative lines. 30

2. A design for a lamp-harp, consisting of a harp approximately **V**-shaped, and provided at its sides with ornamental triangles M, having decorative figures *m*, substantially as shown. 35

3. A design for a lamp-harp, consisting of an ornamental bottom piece, N, partly triangular in form, and two side pieces, M, of triangular form, as illustrated in the drawing. 40

In testimony whereof we have hereunto set our hands in the presence of two subscribing witnesses.

DEXTER W. PARKER.
LEWIS F. GRISWOLD.
